UNITED STATES PATENT OFFICE.

FORD W. HARRIS, OF LOS ANGELES, CALIFORNIA, ASSIGNOR TO PETROLEUM RECTIFYING COMPANY, OF SAN FRANCISCO, CALIFORNIA, A CORPORATION OF CALIFORNIA.

ELECTRIC DEHYDRATOR.

Application filed October 19, 1920. Serial No. 418,059.

To all whom it may concern:

Be it known that I, FORD W. HARRIS, a citizen of the United States, residing at Los Angeles, county of Los Angeles, and State of California, have invented a new and useful Improvement in Electric Dehydrators, of which the following is a specification.

My invention relates to dehydrators used 10 in removing water from petroleum and other oils.

It is a well known fact that if bodies of emulsion are placed between charged electrodes that conducting chains are formed 15 in the mass of emulsion, these chains being made up of the water particles which are thereby caused to agglomerate and form larger masses which will readily settle out of the oil by gravity. Considerable difficulty 20 has been experienced in previous forms of dehydrators due to the fact that these chains form throughout the body of emulsion to be treated and in some cases form in such numbers and with such persistency as to reduce 25 the internal resistance of the treater to a very low value, thus reducing the voltage thereon for the limited current available and shutting off the dehydrating action. This, certain inventors have proposed to 30 prevent by agitating the material in the treater and thus breaking these chains as fast as formed. It is often impractical to agitate the entire mass of the material in the treater to such degree as to prevent this 35 formation and it is further highly desirable that the material in the direct field should not be so agitated.

The principal object of my invention is to provide a treater in which mechanical 40 agitation is dispensed with in the active field but in which the persistence of water chains is prevented.

Further objects and advantages will be made evident hereinafter.

Fig. 1 is a cross section through a preferred form of dehydrator embodying my invention.

Fig. 2 is a figure showing its method of application to an oil tank.

Fig. 3 is a section on a plane indicated by the line 3—3 of Fig. 1.

Fig. 4 is a section through an alternate form of my invention.

Fig. 5 is a plan view thereof.

Fig. 6 is a section of a still different form.

In the form of my invention illustrated in Fig. 1, I provide an outer electrode 11 which is also a container for the emulsion to be treated and an inner electrode 12. The electrode 12 is substantially a cylinder with 60 coned ends 13 and 14. The outer electrode 11 is of such size as to provide a substantially constant arcing distance A between it and the inner electrode. The outer electrode is provided with an inlet tube 15 at 65 the top and an outlet tube 16 at the bottom. Emulsion is introduced through the pipe 17 tangentially into the inlet tube 15 which is provided with a gas vent 18 and with a cover 19 in which an insulator 20 is placed. 70 The insulator 20 is provided with a central rod 21 upon which the inner electrode 12 is hung. The inner electrode is provided with openings 22 and 23 and with a mass of cement or sand 24 which is so distributed 75 as to make it hang perpendicularly and equally spaced from the outer electrode 11. An outlet pipe 30 is provided connecting to the outlet 16.

In practice I prefer to connect the pipe 80 30 to a perforated pipe 31 in the bottom of the tank 32 and to take oil from a higher point in the tank through a pipe 33 by means of a pump 34, this oil being delivered to the pipe 17. The rod 21 is connected 85 through a wire 40 with one side of a secondary 41 of a transformer 42 and the other side of the secondary 41 being connected by a wire 43 with the outer electrode 11. A potential of 11,000 volts is generally sufficient 90 between the electrodes 11 and 12. The tank 32 is provided with a water outlet pipe 37.

In the operation of this embodiment of my invention, emulsion is delivered to the 95 pipe 17 tangentially to the space around the insulator 20 and at a considerable velocity. This velocity is sufficiently high to prevent chain formation over the surface of the insulator and inside the tube 15. The emulsion at a rapidly decreasing velocity passes downwardly over the cone 13 and slows down to a low rate of speed as it passes between the cylindrical portions of the electrodes 11 and 12. In the dehydration of 100 oil, it is necessary that the chains as fast as formed be subjected to sufficient potential to rupture them. This potential is dependent upon the length of the chain and the average size of the particle forming the 110

chain. It is possible to rupture these chains if the gap is short whereas on a long gap, there is not sufficient potential and they form and persist until they short circuit the apparatus.

In the form of my invention illustrated in Fig. 1, the only places in which long chains can form are over the surface of the insulator 20 inside the tube 15 and at the apex of 10 the cone 14 inside the tube 16. At all other points inside the apparatus, the gap is substantially the same and this gap is made sufficiently small to allow for ready rupture of the chains as formed. With this construction, I have found that the emulsion may move very slowly through the field between the cylindrical portions of the electrodes 11 and 12 and the formation of the chains is thereby greatly increased without 15 danger of these chains persisting after they are formed. We have in emulsions certain average size of particle and we have a certain maximum length for a given voltage to which chains may be formed with the assurance 20 that the current density will be sufficient to rupture them after formation. If longer chains are formed they will persist and current will flow through them without rupturing them and in the event that a 25 treater is provided having both long and short distances between the charged surfaces, I have found that the chains will form through the long distance in such numbers as to practically short-circuit the device.

30 I have further found that by maintaining a high velocity, I am able to almost entirely prevent the formation of chains but at the same time I greatly diminish the efficiency and capacity of the apparatus.

35 In the form of dehydrator shown in Fig. 1, I prevent the long chains from forming by providing a high velocity at the points where the emulsion enters and leaves the shell 11 and at the same time I provide a 40 slow velocity in such portions of the apparatus as have only a short gap and in which chains may be formed and disrupted with certainty. In practice, the emulsion is circulated from the pipe 33 through the treater 45 and into the pipe 31. The water tends to settle in the bottom of the tank 32 and may be withdrawn through a pipe 37. The clean oil tends to rise constantly to the top of the pipe and may be withdrawn through the 50

55 pipe 35. In some kinds of oil it is desirable to pass the emulsion upwardly through the shell 11 and the direction of flow is reversed, the pump 34 being connected to the pipe 30 and the pipe 17 being connected to the pipe 31.

60 In Figs. 4 and 6 I show an alternate form of my invention. In the form shown in Fig. 4, a plate 60 is provided inside a casing 61 having an inlet 62 and an outlet 63. A gas vent pipe 64 is provided and emulsion is delivered tangentially through the pipe 65 around the lower portion of an insulator 66 which has a central rod 67 on which the plate 60 is secured. The emulsion enters 65 through the pipe 65 with a whirling motion and is distributed over the plate 60, its velocity being greatly reduced in its passage 70 thereover. The plate 60 is evenly spaced all around from the shell 61 so that the gap is uniform throughout. In the form of 75 my invention illustrated in Fig. 6, two plates 60 and two containers 61 are shown connected in series.

I claim as my invention:

1. An electric dehydrator for petroleum 80 emulsions comprising an outer electrode; an inner electrode supported so that an electric field of substantially uniform thickness is formed between said electrodes; and means for causing a rapid agitation of the emulsion to be treated at all points between said electrodes having a wider separation than the thickness of said field.

2. That step in the art of dehydrating 90 emulsions which comprises forming an electric field of substantially uniform thickness between charged electrodes and simultaneously agitating all portions of the emulsion between said electrodes outside said field.

3. An electric dehydrator for petroleum 95 emulsions comprising: two electrodes between which the emulsion can pass, one electrode having every point of its active surface in contact with said emulsion at a substantially uniform distance from the other electrode; means for passing said emulsion between said electrodes; and means for impressing an electromotive force between said electrodes.

In testimony whereof, I have hereunto set 105 my hand at Los Angeles, California, this 13th day of October, 1920.

FORD W. HARRIS.
